GASOLINE STOVE AND METHOD OF
OPERATING SAME

Milan H. Pinkerton, Marshalltown, Iowa

Application June 6, 1932, Serial No. 615,498

1 Claim. (Cl. 158—53)

The objects of my invention are to provide a gasoline stove of simple, durable and inexpensive construction which may be ignited instantly and without priming, and which when ignited will 5 continue to burn at a maximum efficiency with a minimum of fuel.

A further object is to provide an improved method of operating a gasoline stove, whereby the burners may be instantly ignited without priming, 10 and whereby after it is ignited the operator may, by observing the height and color of the flame at the burner, manipulate a single valve to supply the proper air and gas mixture for producing perfect combustion at the burner.

15 My invention consists in the construction, arrangement and combination of the various parts of the device, and the method of operating same, whereby the objects contemplated are attained, as hereinafter more fully set forth, pointed out in my 20 claim, and illustrated in the accompanying drawing, in which:

Figure 1 shows a perspective view of a stove embodying my invention; and

25 Figure 2 shows an enlarged, detail, sectional view of the gasoline tank and pipes leading to and from it.

Referring to the accompanying drawing, I have used the reference numeral 10 to indicate generally the gasoline tank in which there is placed an air supply pipe 11 leading to a point near the bottom of the tank. 12 indicates a gas supply tank leading from the top of the tank. The tank is preferably filled with blocks or particles 13 of absorbent material saturated with gasoline or similar liquid 35 fuel.

The reference numeral 14 indicates generally an electrically operated fan of ordinary construction, discharging into the air supply pipe 11, which air supply pipe is conducted to positions 40 close to the burners 15, so that air during its passage through the pipe will be warmed during the operation of the stove and delivered to the gasoline tank in warm condition.

The gas supply tank 12 communicates with the 45 burners through pipes 16, each capable of being opened or closed and regulated by a valve 17.

Communicating between the air supply pipe 11 and the gas supply pipe 12 is a secondary air supply pipe 18 in which there is a hand controllable valve 19 to shut off or regulate the amount of air passing through the pipe 18.

In practical operation with my improved stove, I have demonstrated that when the absorbent material within the tank is saturated with gasoline and the fan 14 started, and with the valve

19 closed and one or more of the burner valves 17 opened, then a current of air will be forced through the gasoline tank and deliver a relatively rich gas mixture to the burner, which can be instantly ignited without priming.

As soon as the burner is ignited and the current of warm air is passed through the gasoline tank, then a relatively rich gas mixture will be delivered to the burner, and it will burn with a relatively high flame, which will be of a reddish 10 yellow appearance. Then the operator manipulates the secondary air supply valve 19 and the air from the fan is forced into the gas mixture within the pipe 12, and thereby delivers a thoroughly mixed gas and air supply to the burner, 15 and instantly the height of the flame is reduced and the color of the flame turns to a relatively light blue color, indicating a highly efficient combustion. In this manner the operator may readily and easily deliver the proper mixture of gas and 20 air to the burner for highly efficient combustion.

With my improved stove structure the primary air is forced under pressure through the gasoline and a rich gas is forced into the gas supply pipe of the stove under pressure greater than that 25 of the atmosphere. Secondary air is then forced by pressure into this gas supply pipe and accurately proportioned amounts of rich gas and secondary air may thereby be commingled in the gas supply pipe before entering the burner, because both the primary and secondary air currents are forced into the gas supply pipe under 30 pressure. The relative pressure of the secondary air may be easily controlled by the valve 19 to obtain an ideal mixture in the gas supply pipe 35 under all conditions.

After the valve has once been adjusted, the flame will continue in the burner of the same size and color as it was originally adjusted to, so long as the tank contains the proper amount of 40 fuel.

My improved method of operating the stove consists in delivering a constant supply of warm air through an air pipe in the gasoline tank, and then delivering gas from the gasoline tank to the 45 burners through a gas supply pipe, then igniting one of the burners, then observing the height and color of the flame at the burner, and then manipulating the valve 19 to cause the flow of air from the air supply pipe to the gas supply pipe 50 outside of the tank, and regulating the valve to supply such a quantity of air as to provide the highly efficient mixture of air and gas to the burner, which is determined by the color of the flame. Then when the burner is shut off, the 55

valve 19 is also closed so that when a valve 17 is opened with the fan 14 running, a rich mixture of gas will be forced through the burner for purposes of ready ignition without priming or the like.

5 I claim as my invention:

In a gasoline stove, the combination of a burner, a gasoline supply tank supported below the burner, a fan, a primary air pipe leading from the fan to a point within the gasoline tank below

10 the liquid level therein, a portion of said pipe being arranged close to the burner for heating the primary air and vaporizing the gasoline within the supply tank, a pipe for gas and air leading from the gasoline tank from above the liquid level to the burner, a mixing pipe leading from the primary air pipe to the gas and air pipe and a valve in said mixing pipe for controlling the flow of air into the gas and air pipe.

MILAN H. PINKERTON. 10
